UNITED STATES PATENT OFFICE.

PAUL M. KELLOGG, OF DETROIT, MICHIGAN.

JOURNAL-FEELER.

1,369,032.

Specification of Letters Patent. Patented Feb. 22, 1921.

Application filed May 3, 1920. Serial No. 378,605.

To all whom it may concern:

Be it known that I, PAUL M. KELLOGG, citizen of the United States, residing at Detroit, county of Wayne, State of Michigan, have invented a certain new and useful Improvement in Journal-Feelers, and declare the following to be a full, clear, and exact description of the same, such as will enable others skilled in the art to which it pertains to make and use the same, reference being had to the accompanying drawings, which form a part of this application.

This invention relates to a device, which I have termed a journal feeler, designed to indicate whether or not a journal—particularly a car axle journal—has been "scored" through the entry of grit or other foreign matter between the journal and its brasses.

It is customary at present when examining the condition of an axle journal for the inspector to pass his hand over the surface of the journal to determine whether it has been "scored" or not, but the journal is frequently so hot that an examination of this character cannot be made without danger of injury to the hands of the inspector.

It is therefore one of the objects of the present invention to provide means whereby the journal may be quickly and easily "felt" and if "scored" the depth and extent of same may be determined without danger to the hands of the inspector.

In the accompanying drawings:

Figure 1 is a longitudinal vertical sectional view through a car axle bearing, showing the journal feeler in dotted lines as when testing a journal.

Fig. 2 is a side elevation of the device with parts broken away and in section to more clearly show its construction, and indicating in dotted lines the handle folded back against the body of the device that it may be more readily carried in the pocket.

Fig. 3 is an enlarged cross-sectional view on or about line 3—3 of Fig. 2.

Fig. 4 is an enlarged cross-sectional view on or about the line 4—4 of Fig. 2.

Fig. 5 is an enlarged longitudinal sectional view through the handle showing the battery, and lamp connections.

Fig. 6 is a cross-sectional view through

the handle and lamp socket on or about line 6—6 of Fig. 5.

Referring now to the letters of reference placed upon the drawings:

A, is a slightly tapering tubular arm 60 comprising two opposing portions A' A' secured together by bolts B. The forward end of the tapering arm has a right angle portion A² bored for the passage of a style or stylus C, which projects through the 65 beveled end A³, of the right-angle portion.

D, indicates a swinging rod journaled in a suitable "jeweled" bearing E, secured to the inner wall of the tapering arm. The rod D, is provided at its free end with a 70 pointer D' adapted to traverse a graduated dial E, projecting beyond the opposite end of the tube and integral therewith.

F, is a spring secured at one end in the wall of the tube, its opposite end being 75 formed with a hook to engage the rod D to normally urge the style C, on the end of the rod to project through the inclined or beveled end A³ of the tubular arm as shown in Fig. 2.

G, is a tubular handle, serrated on its outer face to provide a better gripping surface, and provided with a removable closure cap G' at its outer end to admit an electric battery H, urged forward by 85 the action of the spring H'. The handle G is provided with a projecting arm G², pivoted at I to a lug J, integral with the graduated end of the tubular arm.

Adjacent to the graduated dial on the 90 end of the tubular arm is an electric bulb K, supported in a suitable lamp socket K' secured to the end of the tapering arm A. L, denotes a spring latch carried by and forming one of the poles of the battery, 95 adapted to engage a notch in the projecting end of the tapering arm, which together with the spring terminal M, serves to rigidly secure the handle to the end of the tapering arm and to close a circuit between the battery and the lamp K, which is opened upon swinging the handle G to the position shown in dotted lines in Fig. 2.

Having now indicated the several parts by reference letters the construction and 105 operation of the device will be readily understood.

The cover P' of the journal box P having been raised, as indicated in dotted lines in Fig. 1, and the cotton waste removed 110

therefrom; the operator thrusts the device into the journal box that the stylus C may travel over the surface of the bearing, which if grooved or cut will force the stylus to move up and down due to the action of the spring F thereby causing the rod D to swing its pointer D' over the graduated dial E' that the depth and extent of the grooves in the journal may be determined.

10 The light bulb being located adjacent to the dial the device may be used to advantage in the dark as well as in the light.

When the handle is swung back to the position shown in dotted lines the light is 15 thereby turned off, while the device is more readily adapted for the pocket.

Having thus described my invention what I claim is:—

In a device of the character described, a

tubular member having a transverse extension at one end adapted to traverse a journal bearing and an extension provided with a graduated dial at the opposite end, a handle attached to the tubular member, a swinging rod journaled in said tubular member and adapted to traverse said graduated dial, a spring adapted to act upon said rod, and a stylus connected with the swinging rod extending through the transverse extension of the tubular member, whereby it may be brought into impinging relation with an axle journal.

In testimony whereof, I sign this specification in the presence of two witnesses.

PAUL M. KELLOGG.
